(57) **CLAIM**

The ornamental design for a robot for home use, as shown and described.

DESCRIPTION

FIG. 1 is a front perspective view of the robot for home use showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view showing the state of use that the claimed design is sweeping the floor by connecting the cleaning module;

FIG. 9 is a front perspective view showing the state of use that the claimed design is serving the beverages by connecting the serving module; and,

FIG. 10 is a front perspective view showing the state of use that the claimed design is towing the flowerpots by connecting the traction module.

The broken lines depict portions of the robot for home use that form no part of the claimed design. The dash-dot broken lines define the boundary of the claimed design and form no part thereof. The portions of FIGS. 8, 9 and 10 drawn in broken lines show environmental structure only and form no part of the claimed design.
